UNITED STATES PATENT OFFICE

HAROLD FRED ADAMS, OF PROVIDENCE, RHODE ISLAND, ASSIGNOR TO U. S. BOBBIN & SHUTTLE COMPANY, OF PROVIDENCE, RHODE ISLAND, A CORPORATION OF RHODE ISLAND

SHUTTLE EYE

Application filed February 6, 1928. Serial No. 252,093.

This invention pertains to loom shuttles and more particularly to a shuttle eye of self-threading type. Shuttle eyes of this type are generally characterized by having a permanently open channel leading laterally into the longitudinal yarn passage in order to permit free entrance of the yarn during the threading operation. During the flight of the shuttle, the yarn is drawn off from the end of the bobbin and swirls or balloons under the action of centrifugal force, and unless restrained, sometimes slips out through the open entrance channel, leaving the shuttle unthreaded. In one common type of self-threading shuttle eye, a curved horn or arm is arranged to overhang the longitudinal yarn passage in such a manner as to restrain yarn swirling or ballooning in one direction and to prevent it from escaping from the lateral entrance channel. Usually this arm or horn is designed to cooperate with yarn drawn from a bobbin of normal wind and is not effective to prevent escape of yarn swirling or ballooning in the opposite direction, as when drawn from a bobbin of reverse wind. Thus when reversely wound bobbins are substituted for normally wound bobbins, frequent unthreading of the shuttle occurs. In accordance with the present invention, I have provided an improved shuttle eye of the type above referred to but having a simple and efficient guard member which does not in any way interfere with the shuttle threading operation, but which effectively prevents escape of reversely wound yarn from the yarn passage.

In the accompanying drawings, I have illustrated one desirable embodiment of the present invention by way of example, and in the drawings,

Fig. 1 is a fragmentary plan view showing the forward part of a loom shuttle provided with a shuttle eye embodying the present improvements;

Fig. 2 is a side elevation of the improved eye removed from the shuttle body;

Fig. 3 is a side elevation from the opposite side of the shuttle eye;

Fig. 4 is an end elevation of the shuttle eye, looking forward from the bobbin cavity;

Fig. 5 is a section substantially on the line 5—5 of Fig. 3; and

Figs. 6 and 7 are diagrams illustrating the mode of operation of the old and new constructions, respectively.

The shuttle body 1, which may be of wood or any other suitable material, is tapered in usual manner at its forward end 2, and is furnished with the bobbin cavity 3 and with a recess 4 for the reception of the shuttle eye. The bobbin 6 is mounted in the bobbin cavity in any usual manner and the shuttle eye, designated generally by the numeral 7, is secured in the recess 4 by means of the usual retaining bolt.

The shuttle eye here illustrated as embodying the present invention is shown as of integral construction, as for example a casting, which may be of any desired material such as brass or bronze. Although here illustrated as a casting, it is contemplated that it may be made of sheet material suitably bent to shape, or that it may comprise a plurality of independently shaped parts united in any desired manner. This shuttle eye preferably comprises a base member 8 having a concave upper surface providing a longitudinally extending yarn guiding channel 9. A wall 10 extends upwardly in a substantially vertical direction at one side of the channel 9. A top member 11 projects from the upper part of the wall 10 and overhangs the yarn passage. At a point intermediate its ends this top member is provided with depending arm or horn 12. The under sides of the members 11 and 12 form a smoothly curved downwardly concave thread guiding surface.

The lower end 13 of the horn 12 is spaced above the outer edge 14 of the base member 8 and is also preferably disposed adjacent to but inwardly of the outer edge of the yarn guiding channel 9 in the base. This arrangement of the end 13 of the horn 12 leaves a lateral entrance channel or opening 15 leading into the yarn passage and through which the yarn readily enters the passage during the threading operation. As shown in Fig. 1, the horn 12 is spaced from the shuttle body so as to leave ample room for the yarn to move downwardly over the curved outer surface of

the horn 12 and between the latter and the inner surface of the recess 4.

The shuttle eye may be provided with the usual wear-resistant yarn guiding pin 16 and tensioning pad 17, and such other adjunctive features as are common in shuttle eyes of this general class. As thus far described the shuttle eye is of a type which is well known in the art. When a shuttle eye of the kind just referred to is employed with a bobbin of normal wind, the yarn swirls or balloons in the direction indicated by the arrow 18 in Fig. 6, and in thus moving is restrained by the inner surfaces of the parts 8, 10 and 12 of the shuttle eye so that it does not escape outwardly and upwardly through the passage 15. However, if such an eye be employed with a bobbin of reverse wind from which the yarn swirls or balloons in the direction of the arrow 19 in Fig. 6, the parts do not effectively restrain the yarn which tends, while moving upwardly in its circular path, to escape through the channel 15.

To avoid this latter action, my improved shuttle eye comprises a guard post 20 extending upwardly from the base member 8, preferably at the rear end of the latter and at the left-hand side of the yarn passage as viewed in Fig. 4. This post is preferably provided with a concave inner edge or surface 21 which extends upwardly to the point 22 where it is spaced sufficiently from the inner surface of the wall 10 to provide a narrow passage 23 for the entrance of the yarn. The upper end 24 of the post 20 is preferably inclined inwardly and downwardly toward the opening 23 to assist in guiding the yarn into the latter opening.

As indicated in Fig. 4, the inner surfaces of the parts 8, 10 and 12 define a passage of generally oval contour having the narrow entrance opening 23 at its upper end. The surface 21 of the post 20 is preferably disposed slightly to the right, as viewed in Fig. 4, of the lower part of the horn 12 and terminates at a point well above the lower end 13 of the horn. The post 20 may be integral with the base 8 or made as a separate part and secured in position in any desired manner.

In threading the shuttle, the yarn is drawn down into contact with the inclined surface 24 of the post 20 and is guided by said surface into the opening 23. The yarn drops freely through this opening and then engages the upper surface of the horn 12 and follows the latter down into the lateral entrance 15 leading into the longitudinal yarn passage. If the bobbin be of normal wind so that the yarn balloons in the direction of the arrow 18, (Fig. 7) it is restrained from escaping through the lateral entrance opening by engagement with the concave surface 21 of the guard post 20 and also by the action of the horn 12 as above described. On the other hand, if a reverse wound bobbin be employed

and the yarn swirls in the direction of the arrow 19, (Fig. 7) it is restrained in its upward movement by the surface 21 from ballooning outwardly beyond the end 13 of the horn 12, and is thus prevented from escaping through the opening 15. It is thus evident that the guard post 20 provides efficient means for preventing escape of reversely wound yarn from the shuttle eye, while it assists in preventing yarn of normal wind from escaping. I prefer to retain the horn 12.

While I have here shown the guard post 20 as at the extreme rear end of the shuttle eye, I contemplate that it might be otherwise positioned, and while I have shown it as embodied in a shuttle eye of a certain definite type, I wish it to be understood that the broad principle of the present invention is not limited to application to a specific form of shuttle eye, but may be embodied in shuttle eyes of other types.

I claim:

1. A self-threading shuttle eye of the kind having a longitudinal yarn passage provided with an entrance opening along one side and along the top and means to prevent yarn ballooning in one direction from escaping from said opening, said shuttle eye comprising guard means to prevent yarn ballooning in the opposite direction from escaping through said opening.

2. A self-threading shuttle eye of the kind having a longitudinal yarn passage provided with an entrance opening along one side and along the top, a depending horn terminating near the bottom of the yarn passage, said horn having a concave inner surface engageable with yarn ballooning in one direction to prevent the yarn from escaping from the entrance opening, said shuttle eye comprising a guard upstanding from its lower part and having a concave inner surface engageable with yarn ballooning in the opposite direction to prevent its escape through the entrance opening, the horn and the guard being so arranged that their respective end portions extend outwardly beyond the concave inner surfaces which are engageable with yarn during ballooning thereof, whereby the concave inner surface of one of these members may serve to restrain yarn from passing over the end portion of the other of these members.

3. A shuttle eye of the kind having a base provided with a longitudinal yarn-guiding channel, an upstanding longitudinal wall at the inner side of the channel, a top member overhanging the channel and a horn depending from the top member at a point intermediate the front and rear ends of the latter, the lower end of the horn being spaced from the base and terminating at a point within and adjacent to the outer side of the guide channel, said shuttle eye having a guard upstanding from the base at the outer side of the channel and having a concave inner face ter-

minating at a point above and inwardly of the point of the horn and outwardly of the inner surface of the adjacent portion of the horn, whereby said adjacent surface may co-
5 operate with the concave inner face of the guard for preventing escape of yarn ballooning in either direction.

4. In a guide of the class described, the combination of means providing a longitudinal passage having an open side, means for restraining thread in the passage comprising longitudinally spaced and oppositely inclined arms traversing the open side and having inner surfaces which intersect a common longitudinal element of the passage intermediate the ends of the respective arms.

5. In a guide of the class described, the combination of means providing a longitudinal passage having bottom, side and top walls and an open side, means for restraining thread within the passage comprising longitudinally spaced and oppositely inclined arms extending from the top and bottom walls respectively and traversing the open side and having their free ends arranged to engage the thread and to direct the same into the passage.

6. The combination as set forth in claim 1 wherein the arms intersect a common longitudinal element of the passage and the portion of each arm between the common element and the respective top and bottom walls tends to restrain thread within the passage while the remaining portion of one arm 35 serves to direct thread into the passage.

7. In a guide of the class described, the combination of means providing a longitudinal passage having bottom, side and top walls and an open side, and longitudinally spaced and oppositely inclined arms extending from the top and bottom walls respectively and traversing the open side, the free end of each arm being disposed outside of the inner surface of the other arm for engaging thread and guiding the same into the passage, the inner surfaces of the respective arms being arranged to intersect a common longitudinal element of the passage, and the free end of one arm having an oblique surface 50 for guiding thread to the inner surface of said one arm.

8. The combination as set forth in claim 7, and means providing another surface for cooperating with the oblique surface for directing thread into the passage.

9. The combination as set forth in claim 5, wherein the inner surface of the bottom wall is concave and of greater breadth than the top wall and the arm depending therefrom 60 whereby the outer surface of the top wall and of the arm which depends therefrom may serve as a guide for directing thread within the concave inner surface of the bottom wall.

65 10. The combination as set forth in claim

5, wherein the inner surface of the bottom wall is broader than the top wall and the arm which depends therefrom and the outer surface of the top wall and the arm which depends therefrom is a smooth continuous convex surface adapted to direct thread within the bottom wall.

CERTIFICATE OF CORRECTION.

Patent No. 1,772,446.

Granted August 12, 1930, to

HAROLD FRED ADAMS.

It is hereby certified that the above numbered patent was erroneously issued to "U. S. Bobbin & Shuttle Company, of Providence, Rhode Island, a corporation of Rhode Island", whereas said patent should have been issued to "U. S. Bobbin & Shuttle Company, 1929, of Providence, Rhode Island, a corporation of Rhode Island", as assignee of the entire interest in said invention, as shown by the records of assignments in this office; and that the said Letters Patent should be read with this correction therein that the same may conform to the record of the case in the Patent Office.

Signed and sealed this 23rd day of September, A. D. 1930.
